UNITED STATES PATENT OFFICE.

ERASTUS E. WINKLEY, OF LYNN, MASSACHUSETTS, ASSIGNOR TO UNITED SHOE MACHINERY CORPORATION, OF PATERSON, NEW JERSEY, A CORPORATION OF NEW JERSEY.

STOCK-CUTTING MACHINE.

Application filed December 5, 1919. Serial No. 342,656.

To all whom it may concern:

Be it known that I, ERASTUS E. WINKLEY, a citizen of the United States, residing at Lynn, in the county of Essex and State of 5 Massachusetts, have invented certain new and useful Improvements in Stock-Cutting Machines; and I do hereby declare the following to be a full, clear, and exact description of the invention, such as will enable 10 others skilled in the art to which it appertains to make and use the same.

This invention relates to stock-cutting machines and more particularly to machines known in the art as heel-lift dinking machines.

Letters Patent No. 1,291,726, granted Jan. 21, 1919, to William C. Baxter, and assigned to the United Shoe Machinery Corporation, discloses and claims a machine 20 for cutting or dinking heel lifts from sheet material that is moved by successive feeding operations between the elements of the cutting mechanism. In the machine therein described a sheet or strip of material is 25 fed horizontally across a die by means of a pair of intermittently actuated feed rolls and provision is made for locating dies of different sizes at the same distance from the rolls and for adjusting the length of 30 feed in accordance with the size of the die employed. With this construction, inasmuch as the distance from the feed rolls to the die is always the same, irrespective of the size of die employed, provision is made 35 for delaying the introduction of the stock between the feed rolls until after the start of their movement, whenever a die is employed which is wider than the distance from the die to the feed rolls, so as to cause 40 the stock to be fed flush with the near edge of the die by the first feed movement. In order to accommodate the machine to dies of different widths, an initial adjustment of the delaying means is requisite to 45 secure the desired result.

One object of the present invention is to provide certain improvements in machines of the general character above described and to produce a simple, effective and reliable 50 cutting or dinking machine and one which will insure the cutting of a perfect or complete lift from the leading end of each strip of stock fed thereto.

To this end one feature of the present invention contemplates the location of dies

of different sizes in such positions with respect to the feed rolls that the distance from the feed rolls to the nearer edge of the die will always bear the same relation to the width of the die employed, using the term "width" to designate the dimension of the die which coincides with the direction of feed. By means of this arrangement no means for delaying the presentation of the stock to the feed rolls is necessary, and therefore, the preliminary adjustment incident thereto in the prior machine is obviated. It is preferred, however, to employ a gate for the purpose of preventing the stock from being forced between the feed rolls before the rolls start to rotate, and the gate and the feed rolls are so located with respect to each other and to the die that irrespective of the size of the die employed the gate may be opened to admit the stock 70 to the feed rolls coincidently with the start of the feed movement of the rolls.

Another object of the present invention is to prevent any possibility of cutting and feeding imperfect lifts or scrap into the chute which receives the lifts after they have been pushed through the die, and to insure 80 the cutting of complete or perfect lifts only from the material fed to the cutting means.

With this object in view an auxiliary feeding device is provided, for imparting an additional feed movement to the last piece of a strip of stock after it has passed beyond the field of operations of the feed rolls, together with means which insures 85 the operation of the auxiliary feeding device and the closing behind said piece of stock of the gate which controls the presentation to the feed rolls of a succeeding piece of stock. In the preferred embodiment of 90 the invention, said means comprises a stop pin which is actuated, while one piece of material is being intermittently advanced by the main feeding means, to engage the succeeding piece of material after a predetermined 95 number of cycles of the machine, so as to prevent the succeeding piece from butting against the rear end of the first piece during the remaining feed movements 100 of the latter and thus interfering with the operation of the gate and the auxiliary feeding means. The withdrawal of the stop pin from the piece of material which it 105 engages is controlled by the gate, the stop pin being withdrawn only after the closing 110

of the gate behind the preceding piece of material so that the second piece is prevented by the closed gate from passing between the feed rolls until the gate is automatically opened at the beginning of another feed movement.

In addition to the features of the invention above referred to, the present invention also consists in the general arrangement 10 of the machine and in certain devices and combinations of parts tending to simplify and improve the construction and mode of operation of cutting machines, the advantages of which will be obvious to those 15 skilled in the art from the following description.

A cutting machine embodying the various features of the present invention is illustrated in the accompanying drawings, in 20 which:—

Figure 1 is a view in front elevation of the improved lift cutting machine; Fig. 2 is a plan view of the rear portion of a strip of stock illustrating the location thereon of the 25 lift producing cuts; Fig. 3 is a plan view of the lift producing cuts; Fig. 4 is a view in front elevation of the mechanism for controlling the operation of the stop pin; Fig. 5 is a detail sectional view of a portion of the mechanism 30 illustrated in Fig. 4; Fig. 6 is a sectional view taken substantially on the line 6—6 of Fig. 1; Fig. 7 is a perspective view of the strip guiding fingers; Fig. 8 is a detail view 35 illustrating particularly the arrangement of the die, the die-stripper and the strip guiding fingers; Fig. 9 is a perspective view illustrating the manner in which the die-stripper is mounted, the parts being shown in different planes from those they occupy in 40 the machine for clearness of illustration; Fig. 10 is a detail view of a portion of the mechanism shown in Fig. 4; Fig. 11 is a detail plan view showing a die and a die holder of modified construction; and Fig. 45 12 is a view in side elevation of the parts shown in Fig. 11.

The invention is illustrated as embodied in a lift-cutting machine, the cutting and feeding mechanisms of which have the same 50 general construction and mode of operation as that of the machine illustrated and described in Patent No. 1,291,726, previously referred to. In the present machine, however, the arrangement of the feeding mechanism is such as to receive and feed sheet material in a vertical plane instead of in a horizontal plane as in the machine of said patent, and the cutting mechanism is arranged to operate upon the material thus 55 fed so that the lifts cut therefrom may be advanced in stacked formation through the die and into a horizontal straight chute from which they may be removed in stacked relation with facility. In order to enable the 60 invention to be better understood, certain 65

portions of the feeding and cutting mechanisms will be briefly described in this application. For a full and complete description of the parts of said mechanism not fully described herein, reference may be had to 70 said patent.

The operating parts of the present machine are carried by a head 10 that is supported upon a standard 12. A vertical main shaft 14, is journaled in bearings 16 in the head 10 and is connected through intermeshing bevel gears 18 (Fig. 1) with a horizontal shaft 20 that is also journaled in bearings in the head and is continuously driven by a belt pulley 22. Projecting from the top of the main shaft 14 is an eccentric pin 24 (Fig. 3) which serves to reciprocate a pitman 26 that is connected to a plunger 28 carrying at one end a holder 30 for a cutting block 32. The plunger 28 reciprocates in a bearing 34 at the top of the machine, moving the cutting block 32 horizontally into and out of cooperative cutting relation with a die 36. The die 36 is open at both ends so that the lifts cut by the die may progressively pass in stacked formation through the die into a horizontal chute 38 which forms an extension thereof. With this arrangement the lifts may pass through the chute without any change in their direction of movement so that there is no danger of the lifts becoming jammed therein.

The material to be operated upon is fed to the cutting mechanism by means of a pair of toothed feed rolls 40 and 42 (Figs. 1 and 8) which are secured upon vertical shafts 44 and 46, respectively, and are yieldingly pressed toward each other, as described in patent above referred to, in order that they may cooperate to intermittently feed the material as it is introduced between them. The length of feed is adjusted in accordance with the size of the die employed, so as to be just sufficient to feed the strip of stock to the farther edge of the die 100 and to cause it to overlap said edge only far enough to insure the cutting of a complete lift from the stock but not far enough to cause any substantial amount of waste. In other words the length of feed is made 105 equal to the width of the die employed plus the width of the amount of scrap which is to be left between the lifts, and since the width of the scrap is very small the length of feed may be considered to be substantially 110 equal to the width of the die. The term "width" above used and hereinafter appearing in the specification and claims is to be understood as designating the maximum dimension of the die which coincides with the direction of feed of the stock irrespective of the form or arrangement of the die. The means for adjusting the length of the feed 115 is the same as that described in the patent above referred to. In order that the ma- 120

chine may operate upon sheets as well as strips of stock a pair of corrugated cutting disks 48 and 50 are secured upon the respective shafts 44 and 46 and serve to separate the material from which the lifts are immediately to be died, from the sheet as the cutting operation proceeds. Hereinafter, for the sake of brevity and uniformity, the machine will be described as operating upon strips rather than upon sheets of material.

The die 36 is clamped on a die-holder 52 (Fig. 8) between an abutment 54 and a clamp member 56. The die-holder 52 is substantially circular in outline and is provided with a concentric circular shoulder 58 which is seated in a circular opening in the head 10. The die-holder 52 is further provided with a bevelled clamping surface 60 that is adapted to be engaged by the correspondingly bevelled end of a clamping yoke 62 (Figs. 1 and 3) which is held in clamping position by a screw 64.

The present invention contemplates the arrangement of the die in the machine so that the distance from the feed rolls to the nearer edge of the die will always bear the same relation to the width of the die irrespective of the size of die employed, this distance being slightly less, in each case, than the width of the die. In order that this arrangement of the die may be effected with facility and accuracy, a plurality of interchangeable die-holders is provided and a different sized die is secured in place on each of the die-holders at a different distance from the center thereof, before the holders are furnished to the operator, said distance varying directly with the width of the respective dies and the location being such that when the die-holder is seated in the head of the machine and clamped in place, the die carried thereby will be spaced the required distance from the feed rolls.

The material to be cut is guided to the feeding mechanism between vertical side members 66 and 68 (Figs. 1 and 3) and the bottom edge of the material rests upon a horizontal support 70. As the material is fed into position across the die 36 the bottom edge of the material is supported and guided by an edge guide or gage 72 (Fig. 3) which is mounted on a carrier 74 (Fig. 9) that is yieldingly supported to permit movement in the same plane as the cutting block 32, as described in the prior patent, so that while it is normally located in the path of the cutting block, it may be moved with the cutting block as the latter forces the stock into the die.

A die-stripper 76 (Figs. 3, 8 and 9) is provided for stripping the stock from the die as the cutting block returns after each cutting operation. The stripping edge 77 of the die-stripper 76 normally projects beyond the cutting edge of the die, in the path

of the cutting block, and the die-stripper is also mounted on the carrier 74, as shown in Fig. 9, in order that it may be moved yieldingly with the cutting block as the material is cut thereby and forced into the die and be returned to normal position upon the return movement of the cutting block, thereby stripping the stock from the die.

As shown in Figs. 8 and 9, the die-stripper 76 consists of an angle piece one leg of which is secured to the carrier 74 while the other leg thereof is acted upon by means hereinafter described which holds it yieldingly against the bevelled face of the die adjacent the cutting edge thereof. It will be seen that when the die-stripper 76 is moved with the cutting block upon the operative stroke of the latter, it is necessary on account of the bevelled face of the die against which the die-stripper is pressed, that the die-stripper be also permitted to move laterally away from the die a short distance. To this end the leg of the die-stripper which is secured to the carrier 74 is received in a groove 78 formed therein and is held loosely in the groove by means of the head of a screw 79 which extends through a longitudinal slot 80 in the stripper and into the carrier 74.

In order that the die-stripper 76 may automatically adjust itself laterally to dies of different sizes, it is yieldingly urged in the direction of the die at all times by means of a finger 82 (Figs. 3, 7 and 8) which is spring-pressed against the stripper and serves to guide the stock across the die. The guiding finger 82 is pivotally secured to an actuating arm 84 (Fig. 3) by means of a pin 86 which extends through an ear 88 on said finger. The arm 84 is in turn pivoted upon a vertical stud 90 projecting from a portion of the head 10 so that the arm 84 will swing horizontally. A coiled spring 92 acting upon the arm 84 tends to force the guiding finger 82 toward the die. The free end of the guiding finger 82 is loosely supported in a notch 94 in the die-stripper 76. An angle piece 96 projecting from said free end of the guiding finger 82 engages the outer flat side of the die-stripper adjacent the notch 94 so that the stripper is yieldingly held against the bevelled edge of the die by the force of the spring 92 irrespective of the size of the die.

When the stock is being fed toward the die, the guiding finger 82 guides the stock across both the die-stripper and the die. To this end, the guiding finger 82 is acted upon by a coiled spring 98 (Fig. 3) that is secured at one end to an extension of the ear 88 and at its opposite end to an extension of the arm 84, the spring tending to swing the guiding finger so that its free end will move outwardly from the notch 94 and the notch being of such dimensions

that when the die-stripper is seated in the notch the guiding face of the finger 82 is substantially flush with the stripping edge 77 of the stripper.

Cooperating with the guiding finger 82 is a second guiding finger 100 (Figs. 3, 7 and 8) that is adapted to engage the opposite side of the stock as it is fed between said fingers. In order that the guiding finger 100 may be movable with the guiding finger 82 as the latter moves longitudinally to accommodate dies of different sizes, said finger 100 is carried by a bracket 102 that is fastened to the finger 82. The finger 100 is pivoted on a pin 104 (Fig. 7) rising from the bracket 102 and is urged toward the finger 82 by a coiled spring 106, one end of which is secured to a pin 108 depending from the finger 100, and the opposite end 20 to a pin 110 projecting from the bracket 102. The bracket 102, as shown in Fig. 7, is substantially U-shaped to permit the material which is being fed to extend downwardly between the guiding fingers 82 and 25 100.

In addition to the above described features of construction, arrangement and mode of operation of the feeding and cutting means, further provision is made for 30 insuring the cutting of a complete or perfect lift from the leading end of the stock. This means comprises a gate or stop 112 (Figs. 6 and 8) for preventing the stock from being forced manually between the 35 feed rolls before the rolls start to rotate. The gate or stop 112 consists of a bar that is mounted to slide in a guideway 114 and is forked at one end to straddle the guiding finger 100. The gate 112 is movable into 40 and out of the path of movement of the stock and when closed the forked end thereof presents shoulders or abutments 115 (Fig. 6) which are substantially perpendicular to the plane of the stock and serve 45 to temporarily stop the manual advance of a second piece of stock approximately at the bite of the feed rolls, i. e., at the point where the feed rolls grip the stock when the gate is opened. The stop shoulders of 50 the gate are located forward of the vertical axial plane of the feed rolls a distance approximately equal to the width of the scrap to be allowed between the cuts and they are located at a distance from the 55 nearer edge of the die which is substantially equal to the width of the die. The gate 112 automatically opens so as to admit each piece of stock to the grip of the feed rolls coincidently with the start of the feeding 60 movement of the rolls and automatically closes immediately after the piece has passed beyond the field of operations of the rolls. After the gate has been opened to admit a piece of stock to the feed rolls it is held 65 open by means of the stock which is being

fed past it. The opening of the gate is effected by cam actuated mechanism, the cam being brought into operative position at each cycle of operations of the machine, so that the gate will be periodically opened thereby so long as there is no stock present between the feed rolls to hold the gate open.

By locating the shoulders 115 of the gate at the points shown, which are at a distance substantially equal to the width of the die from the nearer edge thereof, and which are also at points slightly forward of the vertical axial plane of the feed rolls and approximately where the rolls grip the stock when the gate is opened, it will be seen that the stock is fed a slightly shorter distance by the first feed movement of the feed rolls than by subsequent feed movements thereof. With the die arranged relatively to the feed rolls, as hereinbefore described, and the length of feed adjusted in accordance with the size of the die employed so as to be slightly in excess of the width of the die, it will be apparent that the first feed movement of the feed rolls will advance the stock approximately to the nearer edge of the die, without overlapping said edge so as to be subsequently cut into the die and that each succeeding feed movement, until the last, will feed the stock far enough so that the leading end will just pass the farther edge of the die. If the machine should operate inaccurately to the extent that a small amount of stock at the leading end of the strip does overlap the die after the first feed movement has taken place and a small piece of scrap is cut into the die, it will fall out of the die upon the withdrawal of the cutting block on account of the arrangement of the die with its cutting edge in a vertical plane.

The mechanism for opening the gate comprises a link 116 (Fig. 6) pivotally connected at one end to a lug 118 extending from the gate 112 through a slot in the guideway 114, and pivotally connected at its opposite end to an arm 120 on a rock shaft 122 that is journaled in suitable bearings in the head, said rock shaft being provided with another arm 124 carrying the roll 126 which cooperatively engages an edge cam 128 on the main shaft 14. A spring 130 is coiled about the rock shaft 122, one end of the spring being fixed to the shaft and the opposite end to one of the bearings therefor, so that the spring will hold the roll 126 against the cam 128 and at the same time tend to hold the gate 112 in operative position.

Inasmuch as it is not possible to locate the cooperating feeding surfaces of the feed rolls immediately adjacent the cutting edge of the die, it might happen after a piece of material has been nearly exhausted, that a portion thereof large enough to produce

a complete lift would be left with its leading edge only part way across the die. Provision has accordingly been made for moving this last piece of material so that the 5 last end of the piece will be advanced into close proximity with the nearer edge of the die. In this way the scrap produced by the cutting operation will be located at the farther side of the die instead of at the 10 nearer side, in which latter case it would be pushed to a position opposite to the die by the advance of the succeeding piece of stock and subsequently forced into the die by the cutting block. To this end, auxiliary feeding means is provided comprising a pair of pusher fingers 132 (Figs. 1 and 3) which 15 normally bear against one side of the stock but do not in any way cooperate with the normal feeding operations of the machine. 20 The pusher fingers 132 are moved toward and from the die 36 at the completion of each feeding movement of the feed roll. In their extreme position away from the die the pusher fingers have their free ends so 25 located that they may engage the rear edge of the last piece of stock to be fed across the die as this edge is released by the feed rolls and inasmuch as the pusher fingers 132 are oscillated only after the feeding 30 movement of the feed rolls has ended they are enabled to spring into position behind the end of the last piece of the strip or sheet of material to give this piece an additional feed movement which will push it into position 35 in the cutting mechanism. These fingers 132 are received in grooves 134 in the feed rolls (Fig. 8) and extend through notches 136 in the stripper member 76. The 40 grooves 134 in the feed roll farthest from the cutting block are deep enough so that when the stock is passing between the feed rolls the fingers 132 may be pressed into the slots against the tension of a spring 138 (Fig. 3) that is connected to an arm 140 45 which is formed integrally with the pusher fingers. The fingers 132 are pivoted at 142 (Fig. 3) upon an oscillating supporting arm 144 that is fulcrumed at 146 upon a bracket 148 on the side of the die support, the supporting arm 144 being oscillated at each 50 cycle of operations of the machine to move the pusher fingers toward and away from the die 36 by suitable connections to the main driving shaft.

55 It is obvious that if it were possible for the operator to keep a second strip of material so closely following the rear end of the strip which is being operated upon by the cutting means that the auxiliary feeding device would be prevented from engaging 60 said rear end, the last mentioned strip would not be given the necessary additional feed movement above referred to and the gate would not be permitted to close in front of the succeeding strip. Accordingly

if a strip of stock passes beyond the field of operations of the main feeding mechanism which is more than large enough to produce a single complete lift, an incomplete or imperfect lift will be cut and forced into 70 the die upon the occurrence of the second successive cutting operation thereafter, said lift consisting of the waste portion at the rear end of the first strip and a portion of the forward end of the succeeding strip. 75

In order to prevent a second strip of material from following so closely the strip which is being operated upon by the cutting mechanism that the pusher fingers 132 and the gate 112 will be prevented from operating, with the result that an incomplete lift may be cut into the die, a stop pin 150 is provided (Fig. 6), together with actuating mechanism therefor, whereby the stop pin is caused to penetrate the succeeding strip of stock for the purpose of arresting its advancing movement. In other words the incoming piece of stock is automatically spaced the proper distance from the end of the preceding piece of stock, although it is presented in abutting relation to said preceding piece of stock by the operator. Means is also provided for timing the penetrative movement of the stop pin so that it will occur after the machine has performed a predetermined number of cycles of operations and a predetermined number of lifts have been cut from the strip of material which is being operated upon. The 80 number of cuts required for cutting across the strips of material which are to be operated upon is preliminarily ascertained by the operator and the stop pin actuating mechanism is then set to cause the stop pin to be actuated during a cycle of operations 85 of the machine preceding the cycle in which the last lift is cut from the strip being operated upon. Preferably the stop pin is operated during that cycle which immediately precedes the one which produces the last lift from the strip. When actuated, the stop pin holds the second strip from following the rear end of the first strip, thus permitting the pusher fingers 132 to engage and advance the last piece of said first strip and 90 allow the gate 112 to close behind it in order that it may perform its function upon said second strip after the latter has been released by the stop pin. 95

100 As shown in Fig. 6, the stop pin 150 consists of a pointed prong projecting from the end of a rod 154 which is adapted to reciprocate in a bearing 156 that is secured to the head of the machine. The rod 154 has a reduced shank portion 158 extending 105 through a sleeve 160 that is adapted for longitudinal movement in the bearing 156. A normally expanded spring 162 encircles the shank of the rod 154 between the inner 110 end of the sleeve 160 and a shoulder 164 at 115 120

125 130

the large end of the rod, and a collar 166 is secured to the free end of the shank portion 158 just beyond the sleeve 160. Normally the stop pin 150 is held retracted 5 from the path of the stock which is being fed to the die by means of a coiled spring 168, one end of which is secured to a pin 170 projecting from the bearing 156, and the opposite end of which is fastened to a 10 pin 172 projecting from the large end of the rod 154 and extending through a slot 174 that is formed at the adjacent end of the bearing 156, the pin 172 serving by engagement with the inner end of the slot 174 to 15 limit the retraction of the stop pin.

Upon the exhaustion beyond a predetermined extent of the piece of stock which is being operated upon by the cutting mechanism, the stop pin 150 is adapted to be 20 advanced yieldingly in a direction to penetrate the succeeding piece of stock by means of the inward movement of the sleeve 160 in the bearing 156. This movement is produced by means of the stop pin actuating 25 mechanism illustrated particularly in Figs. 4 and 6. In the construction therein shown, a pair of pins 176, which project outwardly from opposite sides of the sleeve 160 and extend through slots 178 in the bearing 156, 30 are received in slots 180 that are formed in the opposite sides of the forked arm 182 of a bell crank lever 184. The bell crank lever 184 is secured to a vertical rock shaft 186 that is journaled in bearings in top and 35 bottom supporting plates 188 and 190. The other arm 192 of the bell crank lever 184 is rigidly connected by a vertical rod 194 with an arm 196 that is pinned to the bottom of the shaft 186. The rod 194 is actuated to turn the shaft 186 and the bell 40 crank lever 184, by means of a lever 198 which is rotatably and slidably mounted on the shaft 186, the lever having a downwardly extending hub 200 (Fig. 5) encircling 45 the shaft 186 below the bell crank lever 184 and an upwardly offset portion 202 having an opening above the said bell crank lever through which the shaft 186 extends.

The lever 198 is supported during the 50 feeding of a sheet of material to the cutting mechanism by means of a follower arm 204 on which the lever 198 rests and which comprises a portion of the means for timing the penetrative movement of the stop pin. The 55 follower arm 204 is provided at its free end with internal thread segments adapted to engage with screw threads 206 externally formed on a sleeve 208 that is fastened to a vertical shaft 210 which is journaled in 60 bearings in the top and bottom plates 188 and 190. The follower arm 204 is loosely mounted, as shown in Fig. 5, upon the hub 200 depending from the lever 198 and is confined between the under side of the lever 65 and a collar 214 that is secured to said hub.

A coiled spring 216 encircles the hub of the follower arm 204 and presses it toward the screw 206 to maintain the arm in operative engagement with the screw threads. The shaft 210 is driven continuously during the 70 operation of the machine through intermeshing spur gears 218 and 220 which are secured to the shaft 210 and to the main shaft 14 respectively, and the screw 206 is rotated in the direction of the arrow (Fig. 6) 75 to raise the follower arm 204 and bring the lever 198 into the path of a roller 222 on a crank arm 224 which is secured to the shaft 210 and by which the lever 198 is engaged and oscillated to actuate the stop pin. 80

In order that the stop pin may be held in engagement with the stock a latch 228 (Fig. 6) is pivoted at 230 to an ear projecting from the bearing 156 and is pressed by a spring 232 toward a lug 234 on the arm 192 of the bell crank lever 184 so that when the bell crank lever is swung into operative position a shoulder 235 on the latch 228 will move behind said lug to prevent said bell crank lever from returning to its 90 normal position. With the second piece of stock thus held by the stop pin 150 the preceding piece is advanced beyond the field of operations of the feed rolls and the gate 112 automatically closes behind it. 95

As the lever 198 is oscillated by the crank arm 224 to actuate the stop pin 150 it acts through a lug 236 which it engages on the follower arm 204 to swing the follower arm out of engagement with the screw 206. 100 After being thus disengaged from the screw 206, the lever 198 drops back to its normal vertical position on the shaft. The downward movement of the lever 198 on the shaft is limited by means of a stop device consisting of a bell crank lever 238 (Fig. 4) and an edge cam 240. The bell crank lever 238 is fulcrumed on a stud 241 projecting from the frame, one arm of the lever being forked at its extremity to embrace a hub 244 which is formed on the offset portion 202 of the lever 198 and is provided with pins 246 which project inwardly from the opposite sides of the forked arm into an annular groove 248 in the hub 244, while the other arm of the bell crank lever is provided with an adjustable projection 250 that is arranged to engage the cam 240. The cam 240 is fastened to a horizontal shaft 242 that is adapted to turn in bearings on the top plate 188. A spring 252 one end of which is secured to the longer arm of the bell crank lever 238 and the opposite end of which is secured to a screw 256 in the bottom plate 190, pulls downwardly on said arm with a force varying with the adjustment of the screw and tends to hold the projection 250 against the cam 240. 110

The stop pin 150 is automatically retracted in time to permit the second piece of 120

stock to be advanced against the gate 112 before the gate is again opened. To this end an arm 258 (Fig. 6) projects from the link 116 to a position adjacent a lug 260 on the latch 228, and when the gate 112 returns to operative position upon the final advancing movement of the piece of stock which is being operated upon, the arm 258 is moved to the left in Fig. 6, tripping the latch 228 and permitting the spring 168 to withdraw the stop pin from the succeeding piece of stock.

In order that the means for timing the penetrating movement of the stop pin may not be rendered operative again until the new piece of stock has been introduced between the feed rolls, provision is made for holding the follower arm 204 out of engagement with the screw 206 after the stop pin 150 has been withdrawn from the stock and the lever 198 has been swung back to its normal radial position on the shaft 186. This means comprises a latch 262 (Figs. 4, 6 and 10) which is pivotally mounted for horizontal swinging movement between the opposite arms 264 of a yoke member 266 (Fig. 10) which is also pivotally mounted for horizontal swinging movement between the bottom plate 190 and a boss 268 depending from the top plate 188, said arms 264 having hubs 270 projecting outwardly therefrom which receive pivot pins 272 projecting from the boss 268 and from the bottom plate 190. The latch 262 comprises a blade with a vertically disposed edge 274 which is adapted to cooperate with an arm 276 (Fig. 6) projecting substantially at right angles to the follower arm 204, so that the two arms 204 and 276 constitute a bell crank lever, and the latch 262 is acted upon by a leaf spring 278 that is secured to the yoke member 266, the spring tending to swing the latch into engagement with a stop lug 280 on one of the arms 264.

During the normal operation of the machine the latch 262 is held, by means of the arm 276 in the position indicated in Fig. 6 but upon the disengagement of the follower arm 204 from the screw 206 the latch 262 is moved by the spring 278 into position against the stop lug 280 and behind the end of the arm 276, the vertical edge 274 of the latch engaging a flat surface at the end of the arm 276 and preventing the arm from returning toward the left in Fig. 6, under the influence of the spring 216.

After being released by the stop pin 150 the piece of stock previously held thereby may be advanced manually in the direction of the feeding mechanism only so far as permitted by the gate 112 which is then in operative position in the path of movement of the stock. The operator by pushing the end of the stock against the gate 65 imparts to the stock a tendency to move

the slight distance which is necessary to bring it into the field of operations of the feed rolls and immediately upon the complete withdrawal of the gate the stock is presented to the feed rolls.

It is necessary in order properly to time the engagement of the stop pin 150 with the succeeding piece of stock, that the follower arm 204, which has been disengaged from the screw 206, shall be returned into engagement therewith at the start of the feeding operations upon a new strip. To this end the following provision is made for disengaging the latch 262 from the arm 276. The pivoted end of the latch 262 is periodically oscillated about the pivots of the yoke member 266 by means of an arm 282 projecting from the yoke member 266 and carrying a roll 284 which is adapted to be engaged by the edge cam 128. The cam roll 284 is held against the cam 128 by a spring 286 (Figs. 4 and 10) one end of the spring being fixed to the hub 270 of the yoke member 266 and the other end to the boss 268 on the top plate 188.

A lug 288 projects from the latch 262 and normally oscillates idly with the latch. When, however, the gate 112 is retracted to admit a new strip to the feed rolls, the opposite end of the gate bar is moved into the path of oscillation of the lug 288 and when said lug strikes the end of the gate said end serves as a fulcrum about which the latch is rocked (in a counter clockwise direction in Fig. 6) so as to swing the vertical edge 274 of the latch out of engagement with the arm 276, thus permitting the follower arm 204 to be returned by the spring 216 into engagement with the screw threads 206.

The number of cutting operations which will be performed before the stop pin 150 is actuated to arrest the feed of the piece of stock following the piece that is being operated upon, is determined by the number of turns in the thread of the screw 206 between the follower arm 204 and the top of the screw. The stop pin 150 is actuated to engage the second piece of stock before the last lift is cut from the preceding piece thereby preventing the butting of the second piece against the first piece during the final feed movement of the latter and permitting the auxiliary pusher fingers and the gate to operate.

In order that the stop pin 150 may be operated after the required number of cutting operations have been performed, provision is made for adjusting the radial position of the edge cam 240. To this end a crank arm 290 is secured to the top of the shaft 242 to which the cam is secured, and the crank arm is provided with a handle 292 and a suitable detent 294 which is pressed downwardly in any suitable manner so as to engage with a series of holes 296 in a

gage plate 298 which is secured to the top plate 188. The holes 296 are so spaced apart on the gage plate 298 that by turning the handle 292 from one to another the normal position of the follower arm 204 may be shifted from one turn of the screw thread 206 to another turn thereof. It will be observed that the vertical edge 274 of the latch 262 extends through such a distance that the follower arm 204 is held in its disengaged position at any point within its range of vertical movement. The operator having first ascertained the number of cuts required for cutting across the sheet of material which is to be operated upon, sets the stop pin actuating mechanism by turning the handle 292 until the detent 294 engages the proper hole in the gage plate 298 to cause the stop pin to be actuated during the desired cycle of operations of the machine preceding the final cycle.

Figs 11 and 12 illustrate a die and die-holder of modified construction which may be adopted for the purpose of permitting the insertion of dies of different sizes in a single die-holder and thus avoiding the necessity of providing a separate die-holder for each of the various sizes of dies employed. As therein shown, a die 300 is formed with a flat rim 302 projecting outwardly from its base parallel to the plane of the cutting edge of the die, the rim extending entirely around the die and having a rectangular marginal contour. The die 300 is adjustably secured upon a pair of die-supporting plates 304 which are in turn adjustably secured upon a die-holder 306. To this end the plates 304 are each provided with shoulders 308 which are adapted to engage opposite edges of the rim 302 so as to confine the die between said shoulders and the plates are secured to the die-holder with provision for adjustment toward and from each other so that the shoulders 308 may be positioned to accommodate dies of different sizes. The means for adjustably securing each plate 304 to the die-holder comprises a bolt 310 which projects from the die-holder 306, extending through a slot 312 in the plate 304, and is provided with a nut 314 which engages the outer face of the plate and clamps the plate against the die carrier. Each plate 304 is guided, as it is adjusted, by means of a lug 316 (Fig. 12) which projects from the plate into a slot 318 in the die carrier 306 extending at right angles to the shoulder 308, the lug and slot cooperating to maintain the shoulders 308 in parallelism with each other. The plates 304 are cut away at 319 to permit the lifts cut by the die to pass through the die and into a suitable chute or receiver. In order that the die 300 may be clamped in adjusted position on the supporting plates 304, each plate 304 is provided with a bolt 320, projecting out-

wardly adjacent the shoulder 308 and having a washer 322 and nut 324 thereon, the washer 322 overlapping the rim 302 of the die 300 and being forced against the rim by the nut 324 so as to clamp the rim against the plate 304.

With the above described construction and arrangement of the die-holder 306, the die-supporting plates 304 and the die 300, it will be seen that dies of different sizes may be readily inserted in the die-holder so that it is necessary to furnish only one die-holder for the different dies employed. The die-holder 306 is adapted to be placed in position in the machine in the same manner as the die-holder 52 hereinbefore described, and the arrangement of the plates 304 upon the die-holder 306 is such that the shoulders 308 extend horizontally when said die-holder is clamped in position. It will therefore be seen that by adjusting the plates 304 toward and from each other the vertical adjustment of the die in the machine may be effected, whereas the horizontal adjustment of the die toward or from the feed rolls may be effected by sliding the die horizontally between the guiding shoulders 308.

While it is preferred to employ the specific construction and arrangement of parts shown and described, it will be understood that this construction is not essential except so far as specified in the claims, and may be changed or modified without departing from the broader features of the invention.

The invention having been described, what is claimed is:

1. A stock-cutting machine having, in combination, means for feeding the stock in a series of steps, cutting means for successively cutting blanks from the stock as it is fed, and means acting in conjunction with said feeding and cutting means for controlling in a positive manner the introduction of the incoming stock with relation to the preceding piece of stock and thus insuring the cutting of perfect blanks at the extreme forward and rear ends of the stock.

2. A stock-cutting machine having, in combination, feed rolls for feeding the stock in a series of steps, actuating means for the feed rolls adjustable to vary the length of feed of the stock, a stop arranged adjacent the bite of the feed rolls and normally operative to prevent the introduction of the stock between the rolls, and cutting means including a die spaced from said stop a distance substantially equal to the length of the feed and the width of the die for successively cutting blanks from the stock as it is fed.

3. A stock-cutting machine having, in combination, means comprising feed rolls for feeding the stock in a series of steps, actuating means for the feed rolls adjust-

- able to vary the length of feed of the stock, cutting means including a die spaced from the feed rolls a distance substantially equal to the length of the feed and the width of 5 the die for successively cutting blanks from the stock as it is fed, and means acting in conjunction with said feeding and cutting means for determining the time of introduction of the incoming stock to position 10 it properly with respect to both the preceding piece of stock and the die thus insuring the cutting of perfect blanks at the extreme forward and rear ends of the stock.
- 15 4. A stock-cutting machine having, in combination, means for supporting a piece of stock, means for controlling and feeding the stock, means for successively cutting blanks from the stock as it is fed, said controlling and advancing means and said cutting means being constructed and arranged to engage and hold the incoming stock for a predetermined period to space said piece of stock properly with respect to the preceding piece so that the incoming stock may be controlled to insure the cutting of a perfect blank at the leading end of the stock, and means cooperating with said first means for insuring the cutting of a perfect blank 20 at the extreme rear end thereof.
- 25 5. A stock-cutting machine having, in combination, a pair of feed rolls for advancing the stock in a series of steps, and cutting means for successively cutting blanks from the stock as it is advanced, said cutting means including one of a plurality of interchangeable die-holders each having a die of a different size so positioned thereon that when a particular die-holder is used 30 in the machine its die will be located at a distance from the common axial plane of the feed rolls substantially equal to the width of said die.
- 35 6. A stock-cutting machine having, in combination, a pair of feed rolls for advancing the stock in a series of steps, cutting means for successively cutting blanks from the stock as it is advanced, said cutting means including one of a plurality of 40 interchangeable die-holders each having a die of a different size so positioned thereon that when a particular die-holder is used in the machine its die will be located at a distance from the common axial plane of the feed rolls substantially equal to the width of said die.
- 45 7. A stock-cutting machine for operating upon successive strips of stock having, in combination, means for supporting a strip 40 of stock, means for feeding said strip, means for cutting blanks successively from said strip as it is fed, means for supporting a second strip while it is advanced in butting end-to-end relation with the first strip, and means acting in conjunction with 50 said cutting and feeding means for spacing the pieces of stock presented in butting end-to-end relation by the operator thus insuring the cutting of a perfect blank at the extreme end of each strip.
- 55 8. A stock-cutting machine having, in combination, a pair of feed rolls for imparting successive feed movements to the stock and adapted to be adjusted to vary the length of the feed movements, and means for receiving and locating in the machine one of a plurality of interchangeable die-holders each having a die of a different size so positioned thereon that when a particular die-holder is used in the machine its die will 60 be located at a distance from the common axial plane of the feed rolls equal to the width of said die, whereby the machine may be set by adjusting the length of feed and selectively using the interchangeable die-holders to cut a perfect blank at the leading end of the stock irrespective of the size of die employed.
- 65 9. A stock-cutting machine having, in combination, cutting means comprising one of a plurality of different sized dies adapted to be interchangeably received in the machine, a pair of feed rolls for advancing the stock across the die, and means for supporting the die so that irrespective of the size of the particular die used, the distance from the nearer cutting edge thereof to the common axial plane of the feed rolls will be substantially equal to the width of 70 said die.
- 70 10. A stock-cutting machine having, in combination, a pair of feed rolls, and cutting mechanism including one of a plurality of interchangeable unitary structures, each comprising a die-holder and a die rigidly secured thereto, the dies being differently located on their respective die-holders so that by selectively using said unitary structures the dies may be positioned in the machine at different distances from the feed 75 rolls.
- 80 11. A stock-cutting machine having, in combination, feed rolls for feeding a strip of stock, means including a die for successively cutting blanks from the stock as it is fed, a die-support adjustable toward and from the feed rolls, and an auxiliary feed device arranged to engage the strip after it has passed beyond the feed rolls and movable through distances varying in accordance 85 with the location of the die-support to feed the strip across the die until its rear extremity is advanced substantially to the near edge of the die.
- 90 12. A stock-cutting machine having, in 95

combination, cutting means including a die, a pair of feed rolls for feeding the stock to the die, said rolls being arranged with their axes in a plane at a distance from the nearer cutting edge of the die slightly less than the width of the die and adapted to impart feed movements to the stock slightly greater than the width of the die, a gate located forward of the axial plane of the feed rolls and approximately at a distance from said edge of the die equal to the width of the die, and means for opening the gate to admit the stock to the grip of the feed rolls at the start of the first feed movement thereof.

13. A stock-cutting machine having, in combination, a pair of feed rolls for advancing the stock by a series of steps, cutting means comprising a die, and a gate normally closed to prevent the introduction of the stock to the feed rolls and adapted to be opened coincidently with the start of the feed movement of the rolls to admit the stock to the rolls, the gate and the feed rolls being so constructed and so arranged with respect to the die that the stock will be advanced only to the nearer edge of the die at the first feed movement so as to avoid the cutting of scrap into the die.

14. The combination in a stock-cutting machine adapted to interchangeably receive dies of different sizes, of a die, a die-stripper located adjacent the die, and means permitting the die-stripper to automatically adjust itself to dies of different sizes.

15. The combination in a stock-cutting machine of a die having a bevelled outer face adjacent its cutting edge, a cutting block adapted to cooperate with the die to cut the stock, and a die-stripper in contact with said face and normally projecting beyond said cutting edge into the field of operations of the cutting block, the die-stripper being mounted to permit yielding movement in a direction parallel to the axial length of the die and laterally away from the die.

16. The combination in a stock-cutting machine adapted to interchangeably receive dies of different sizes, of a die, means for engaging sheet material close to the die to guide it across the die, said means being adapted to adjust itself to dies of different sizes so as to engage the stock at the same distance from the die irrespective of the size of the die.

17. The combination in a stock-cutting machine adapted to interchangeably receive dies of different sizes, of a die, a guiding member adjacent the die for guiding sheet material across the cutting edge thereof, and means for causing the member to automatically adjust itself to dies of different sizes.

18. The combination in a stock-cutting

machine adapted to interchangeably receive dies of different sizes, of a die, a pair of guiding members adapted to engage opposite sides of a sheet of material at points adjacent the die to guide it across the die, and means for causing the members to automatically adjust themselves to dies of different sizes.

19. The combination in a stock-cutting machine adapted to interchangeably receive dies of different sizes, of a die, a die-stripper located adjacent the die and adapted for lateral movement toward and from the die to accommodate dies of different sizes, a member for guiding the stock across the die said member being yieldingly held in engagement with the stripper to force the stripper against the die.

20. A stock-cutting machine having, in combination, feed rolls for advancing pieces of stock successively presented thereto, a gate for controlling the presentation of the stock to the feed rolls, cutting means for successively cutting blanks from the stock as it is fed, and means for preventing a succeeding piece of stock from following the preceding piece so closely as to interfere with the operation of the gate.

21. A stock-cutting machine having, in combination, feed rolls for advancing pieces of stock successively presented thereto, cutting means for successively cutting blanks from the stock as it is fed, an auxiliary feed device for engaging the rear end of the stock after it has passed beyond the field of operations of said feeding means and pushing it toward the cutting means, and means for preventing a succeeding piece of stock from following the preceding piece so closely as to prevent the operation of said auxiliary feed device.

22. A stock-cutting machine having, in combination, feed rolls for advancing pieces of stock successively presented thereto, a gate for controlling the presentation of the stock to the feed rolls, cutting means for successively cutting blanks from the stock as it is fed, an auxiliary feed device for engaging the rear end of the stock after it has passed beyond the field of operations of the feed rolls and pushing it toward said cutting means, and means for preventing a succeeding piece of stock from following the preceding piece so closely that the gate and the auxiliary feed device are prevented from operating.

23. A stock-cutting machine having, in combination, cutting means, means for feeding stock to the cutting means, an auxiliary feed member for engaging the end of the stock after it leaves said feeding means and pushing it toward said cutting means, a holding device for preventing the advance of a second piece of stock from interfering

with the operation of said auxiliary feed member, and means for retracting the holding device from the stock.

24. A stock-cutting machine having, in combination, cutting means, means for feeding stock to the cutting means, an auxiliary feed member for engaging the end of the stock after it leaves said feeding means and pushing it toward said cutting means, a holding device for preventing a second piece of stock from following the preceding piece so closely as to prevent said auxiliary feed member from operating, means for controlling the time of operation of the holding means, and means for rendering the holding means inactive.

25. A stock-cutting machine having, in combination, cutting means, means for intermittently feeding sheet material to the cutting means, a pusher for engaging the end of the material as it leaves said feeding means and pushing it to the cutting means, a holding device for preventing a second piece of material from butting the preceding piece when it is ready to be engaged by said pusher, a timing device for controlling the operation of the holding device, means for varying the setting of the timing device, and means for releasing the holding device.

26. A stock-cutting machine having, in combination, cutting means, means for feeding pieces of stock to the cutting means, an auxiliary feed member for engaging the rear end of the stock and imparting an additional feed movement thereto after it has passed beyond the field of operations of said feeding means, and means operating after the performance of a predetermined number of cycles of operations of the machine for preventing the butting of a second piece of stock against the rear end of the first piece, thereby permitting the auxiliary feeding means to operate upon the latter.

27. In a stock-cutting machine, feeding mechanism comprising a feed roll, a gate for controlling the presentation of the material to be fed to the feed roll, means for automatically moving said gate out of the path of the feed movement of said material, and means for preventing a second piece of material from following so closely the preceding piece as to prevent said gate from returning to normal position after each piece of material fed passes beyond said feed roll.

28. A stock-cutting machine having in combination, cutting means, means for feeding stock to the cutting means, a gate for controlling the presentation of the stock to the feeding means, means for automatically moving said gate out of the path of movement of the stock, a holding device for preventing the advance of a second piece of stock after a predetermined number of blanks have been cut from the preceding piece, and means

controlled by said gate for retracting said holding device from the stock.

29. A stock-cutting machine having in combination, cutting means, means for feeding stock to the cutting means, a gate for controlling the presentation of the stock to the feeding means, means for intermittently withdrawing the gate from operative position to permit the feeding of the stock, a holding device for preventing the advance of a second piece of stock, and means actuated by the return of the gate to operative position after a piece of stock has passed beyond it for releasing the holding device from the succeeding piece of stock.

30. A stock-cutting machine having, in combination, cutting means, a main feed device for feeding stock to the cutting means, an auxiliary feed member for engaging the end of the stock after it leaves said device and pushing it toward said cutting means, a holding device for preventing the advance of a second piece of stock from interfering with the operation of said feed member, a timing device for controlling the operation of the holding device, means for maintaining the timing device inoperative until a second piece of material has been presented to the main feed device, and means for releasing the holding means.

31. A stock-cutting machine having, in combination, cutting means, means for feeding pieces of stock successively to the cutting means, a gate for controlling the presentation of the stock to the feed means constructed and arranged to be held open by the presence of stock within its path of movement, means tending to close the gate, means for yieldingly holding the gate against the stock as the stock is being advanced by the feeding means, means for automatically opening the gate, a holding device for arresting the advance toward the gate of a second piece of stock to prevent said piece from interfering with the closing movement of the gate, a timing device for controlling the holding device, and means for maintaining the timing device inoperative when the gate is closed.

32. A stock-cutting machine having, in combination, cutting means, means for feeding pieces of stock successively to the cutting means, a gate for controlling the presentation of the stock to the feed means constructed and arranged to be held open by the presence of stock within its path of movement, means tending to close the gate, means for yieldingly holding the gate against the stock as the stock is being advanced by the feeding means, means for automatically opening the gate, a holding device for arresting the advance toward the gate of a second piece of stock to prevent said piece from interfering with the closing

movement of the gate, a timing device for controlling the holding device, means for maintaining the timing device inoperative when the gate is closed, and means depending upon the presence within the path of movement of the gate of a second piece of stock for restoring the timing device to operative condition.

33. A stock-cutting machine, having, in combination, means for successively cutting blanks from a strip of stock, mechanism including a pair of intermittently actuated feed rolls for feeding the stock to the cutting means, a stop projecting into the path of the stock, means for spacing the pieces of stock introduced in butting relation by the operator, and means for withdrawing the stop at the start of rotation of the feed rolls.

34. In a machine of the character described, means comprising a die for cutting blanks from sheet material, means comprising intermittently actuated feed rolls for feeding the sheet material to the die, a stop arranged to project into the path of the material to position it properly with respect to the feed rolls and to be withdrawn at the start of rotation of the feed rolls, and means for spacing an incoming piece of material from the preceding piece so that the stop can operate to position the incoming piece of material.

35. In a machine of the character described, means comprising a die for cutting blanks from sheet material, means comprising intermittently actuated feed rolls for feeding the sheet material to the die, a stop arranged to project into the path of the material to position it properly with respect to the feed rolls and to be withdrawn at the start of rotation of the feed rolls, and a member for engaging an incoming piece of material so as to make a space between it and the preceding piece of material in which the stop can be projected to position the incoming piece of material with respect to the feed rolls.

36. In a machine of the character described, means for operating upon sheets of material, means for feeding the material, and means for automatically spacing the sheets of material presented in abutting relation and for positioning the sheets properly with respect to the first-mentioned means.

37. In a machine of the character described, means for operating upon sheets of material, means for feeding the material, means co-operating with the feeding means for positioning the material with respect to the first-mentioned means, and means for spacing the successive sheets of material relatively to each other so that the positioning means may operate effectively.

38. In a machine of the character described, means for cutting blanks from

sheet material, means for feeding the material to the cutting means, means co-operating with the feeding means for positioning the material with respect to the cutting means, and means controlled by the positioning means for spacing successive sheets of the material presented in abutting relation by the operator.

39. In a machine of the character described, means comprising a die for cutting blanks from sheet material, means comprising intermittently actuated feed rolls for feeding the material to the die, a stop arranged to project into the path of the material and to be withdrawn at the start of rotation of the feed rolls, the said stop operating to position the material so that the latter will be properly presented by the feed rolls to the die for the cutting of the first blank, and a member controlled by the stop for spacing the incoming sheets of material as they are presented in abutting relation by the operator so that the stop may engage the front end of each sheet in functioning as a positioning means.

40. In a machine of the character described, means for operating upon sheets of material, means for feeding the sheets, a stop arranged to project into the path of the material to position it properly with respect to the feeding means, and to be withdrawn at the beginning of the operation of the feeding means, and means for spacing an incoming piece of material from the preceding piece so that the stop can operate to position said incoming piece.

41. In a machine of the character described, means for cutting blanks from sheet material, means for feeding the material to the cutting means, and means for automatically spacing sheets of material moving in abutting relation toward the feeding means.

42. In a machine of the character described, means for cutting blanks from sheet material, means for feeding the material to the cutting means, and a member arranged to engage a surface of the incoming sheet of material for spacing successive sheets of the material relatively to each other so that they may be operated on separately by the cutting means.

43. In a machine of the character described, means for cutting blanks from sheet material, means for feeding the material to the cutting means, a piercing member arranged to engage and hold an incoming sheet of the material to space it from the preceding sheet and operated in properly timed relation to the feeding means so that the sheet may be presented to the cutting means for predetermined cutting operations.

44. In a machine of the character described, means comprising a die for cutting blanks from sheet material, means comprising intermittently actuated feed rolls for

feeding the material to the die, a stop arranged to project into the path of the material and to be withdrawn at the start of rotation of the feed rolls, the said stop 5 operating to position the material so that the latter will be properly presented by the feed rolls to the die for the cutting of the first blank, and a piercing member controlled by the stop for engaging and holding 10 the incoming sheets of material as they are presented in abutting relation by the operator to space each sheet from that immediately preceding so that the stop may engage the front end of each sheet in functioning 15 as a positioning means.

45. In a machine of the character described, a die having a flange extending laterally in a plane parallel with the plane of the cutting edge of the die, a pair of 20 die supporting plates adjustable toward and from each other to clamp the flange of the die, a die holder, and means for securing the die supporting plates and the die to the holder.

46. In a machine of the character described, a die having an integral flange extending laterally from the die in a plane parallel with the cutting edge of the die, a pair of die supporting plates having shoulders to engage and position the flange 25 30 of the die, a die holder, a pair of bolts one on each side of the die operative to engage

the flange of the die and the die holder to hold the die, the die supporting plates and the die holder assembled as a unit.

47. In a machine of the character described, a die having a rectangular flange in a plane parallel with the plane of the cutting edge of the die, a pair of die supporting plates having each a shoulder to engage a straight edge of the flange so that 35 said plates form a guideway in which the die is adjustable, a die holder, and means for adjustably securing the die supporting plates and the die vertically on the holder.

48. In a machine of the character described, a die having a rectangular flange in a plane parallel with the plane of the cutting edge of the die, a pair of die supporting plates having each a shoulder to engage 45 a straight edge of the flange so that said 50 plates form a guideway in which the die is adjustable, a die holder, and means for adjustably securing the die supporting plates and the die vertically on the holder, said 55 means comprising two pairs of bolts and slotted portions of the die supporting plates whereby the die supporting plates are held in perfect alignment with respect to the flange of the die during all movements of adjustment.

ERASTUS E. WINKLEY.
